Beverly Hills, Calif., assignors to Jump-Jump
Franchise Corp., Los Angeles, Calif., a corporation of New York

Application November 20, 1948, Serial No. 149,735

Term of patent 3½ years

(Cl. D34—2)

To all whom it may concern:

Be it known that we, Mary McConnell Hickox and Harry M. Hickox, both citizens of the United States of America, residing at Beverly Hills, in the county of Los Angeles, State of California, have invented a new, original, and ornamental Design for a Toy Animal, of which the following is a specification, reference being had to the accompanying drawing, forming a part thereof.

We claim:

The ornamental design for a toy animal, substantially as shown.

MARY McCONNELL HICKOX,
HARRY M. HICKOX.
